UNITED STATES PATENT OFFICE.

EUGENE ATWOOD AND CHARLES H. COWAN, OF STONINGTON, CONNECTICUT, ASSIGNORS TO THE ATWOOD MACHINE COMPANY, OF SAME PLACE.

BOBBIN.

SPECIFICATION forming part of Letters Patent No. 371,296, dated October 11, 1887.

Application filed May 8, 1884. Serial No. 130,717. (No model.)

To all whom it may concern:

Be it known that we, EUGENE ATWOOD and CHARLES H. COWAN, both of Stonington, in the county of New London and State of Connecticut, have invented a new and useful Improvement in Bobbins, of which the following is a specification, reference being had to the accompanying drawings, forming part of this specification.

- 10 The iron-headed bobbins used in spinning commonly have the iron heads composed of flat disks of wrought-iron plate secured by screws to the ends of the wooden body or barrel, and have the journals formed of the 15 ends of an axle consisting of a piece of rod-iron driven tightly into the barrel and heads. Commonly the tight fit of the axle is all that keeps it in place, and the result is that with rough usage the axle is apt to be displaced.
- 20 Sometimes the axle is secured by pinning through it and the body or barrel transversely.

The object of this invention is to obtain an iron-headed bobbin the journals of which will not be liable to displacement, and which is 25 less costly than one in which the heads are secured to the barrel by screws and the axle is secured in the barrel by a transverse pin; and to this end the invention consists in an iron-headed bobbin having the journals integral with the heads, and having the heads 30 secured to the barrel by means of a screw-threaded central bolt or connection onto which the heads are screwed.

It also consists in a novel construction of 35 the inner faces of the heads, as hereinafter described, whereby they are centered to the heads and are made to give them a good hold upon the central bolt or connection.

Figure 1, in the drawings, is an external 40 longitudinal view of a bobbin constructed according to our invention. Fig. 2 is a central longitudinal section of the same, with the central bolt in elevation.

Similar letters of reference indicate corresponding parts in the several figures.

A is the wooden barrel, B B are the heads, and C is the central bolt forming the connection between the heads.

The barrel is bored centrally considerably

larger than the central bolt. The heads are 50 made of cast-iron, having on their inner faces concentric hubs b b, which fit the ends of the bore a of the barrel, and having on the outer faces the journals d d, which are integral with them, being parts of the same casting. The 55 hubs are centrally bored and tapped to receive and fit the screw-threaded ends of the central bolt, C, and are long enough to give a substantial hold on the bolt or axle. There are in the inner faces of the heads, surrounding 60 the hubs b b, annular recesses e e, which receive the ends of the barrel in such a manner as to prevent the silk or other thread from entering between the barrel and the heads.

To assemble the parts to make a complete 65 bobbin, one of the heads is screwed onto one end of the central bolt, the barrel is then placed over the said bolt and on the hub of the head, and the other head is then screwed onto the other end of the bolt far enough to 70 clamp the heads tightly against the ends of the barrel, and so secure all the parts very firmly together.

The journals may be milled or turned true, and the hubs b b may also be milled or turned 75 to make them fit properly into the ends of the bore of the barrel.

What we claim as our invention, and desire to secure by Letters Patent, is—

1. The combination of the barrel, the separate heads having the journals integral with them, and the central bolt or connection having the heads screwed on the ends thereof, substantially as herein described.
2. The combination of the barrel A, the heads B, having integral journals d, recesses e, and tapped hubs b, and the central bolt, C, screw-threaded to fit the said hubs b, substantially as herein described.
3. The combination of the barrel A, the heads B, with the hubs b and recesses e, and the central rod, C, screw-threaded to fit the hubs b, all substantially as herein set forth.

EUGENE ATWOOD.
C. H. COWAN.
